UNITED STATES PATENT OFFICE.

GLENN HENRY BOLUS, OF MANSFIELD, OHIO, ASSIGNOR TO THE OHIO BRASS COMPANY,
OF MANSFIELD, OHIO, A CORPORATION OF NEW JERSEY.

HANGER FOR TROLLEY-WIRES.

1,121,607.

Specification of Letters Patent. Patented Dec. 22, 1914.

Application filed February 9, 1912. Serial No. 676,517.

To all whom it may concern:

Be it known that I, GLENN H. BOLUS, a citizen of the United States, residing at Mansfield, in the county of Richland and State of Ohio, have invented certain new and useful Improvements in Hangers for Trolley-Wires, of which the following is a specification.

My invention relates to suspension devices for electric conductors, and has particular reference to improvements in trolley wire hangers of the type generally known as catenary hangers.

The primary object of my invention is to provide an improved hanger for trolley wires which will be simple and durable in construction and inexpensive to manufacture; which will positively and securely hold the trolley wire, and which may be easily and quickly attached or detached from the wire without disturbing or damaging it in any manner.

Another object of my invention is to provide an improved catenary hanger embodying a wire clamping and holding member formed or pressed from a single piece of metal.

With these and other hereinafter apparent objects in view, my invention consists in the features of novelty disclosed in the construction, combination and arrangements of parts shown in the accompanying drawings, which illustrate one embodiment of my invention, and in which—

Figure 1 is a view in elevation showing my improved hanger. Fig. 2 is an end view partly in section on the line 2—2 of Fig. 1. Fig. 3 is a side or face view of the clamping member without the clamping bolts. Fig. 4 is a top view thereof, and Fig. 5 is a fragmentary view in section on substantially the line 5—5 of Fig. 2 showing the relation of the clamping member and the suspension member.

My invention is shown in the drawings as embodied in a catenary hanger for use more particularly with trolley wires of the so-called grooved and figure 8 types, but it will be readily apparent, after an understanding of my invention has been obtained from the disclosures herein made, that my improved hanger may by suitable modification, be adapted to other types of trolley wires, such as the round wire, without departing from the spirit of the invention.

In catenary line construction for electric railway, it is desirable that the hangers used for suspending the trolley wire be as light in weight as possible, consistent with the proper strength and durable. It is also desirable that the hangers be made of the fewest possible number of parts, that they be capable of being manufactured at minimum expense, and that they be capable of being readily and easily attached to or detached from the trolley wire, without sacrifice to the proper functions of the hangers. My improved hanger, shown in the drawings, is what I regard as the best form, and meets all of these requirements. It will be seen that the hanger member A, which is attached or clamped to the trolley wire B (the so-called grooved type being shown) is preferably composed of a piece or "blank" of sheet metal. This blank of metal is preferably substantially rectangular, although it may be of any suitable geometrical shape. In the form shown the metal is bent or formed along substantially its center, that is to say, it is doubled upon itself to form a member which is substantially U shaped in cross section. Although the bend may be made in any manner or form best adapted to the particular requirements, I prefer to make the bend 1 in the sheet metal upon a radius substantially equal to or a trifle less than the radius of the trolley wire to which the hanger is to be attached, as shown in Fig. 2. It will also be seen that with this formation the sides 2 and 3 are substantially parallel and tangentially disposed with respect to the trolley wire. Hence the hanger is substantially no thicker than the diameter of the trolley wire to which it is attached, and offers no obstruction to the travel contact member which engages the trolley wire, whether this contact member be the usual form of trolley wheel or whether it be of the roller type as used on pantographs. The lower edges or lips 4 and 5 respectively are preferably turned inwardly so as to properly engage the trolley wire. The particular formation of these lips depends upon the type of trolley wire used. As before mentioned, I have shown my improved hanger in connection with the grooved type of trolley wire, and these lips are inturned substantially as shown in Fig. 2 to adapt the hanger to the grooved or figure 8 type of trolley wire.

In order that the member A may be firmly clamped or attached to the trolley wire, preferably in such manner that it may be readily detached therefrom, if desired, I provide several bolts 6 or screws, which are adapted to draw the two sides 2 and 3 toward each other to secure the proper clamping effect. Any suitable type of clamping bolt may be used, but I prefer that the bolts be so associated with the member A that they will not project beyond the planes of the side faces 2 and 3, whereby the clamping or hanger member may be generally smooth and flat as a whole. For these reasons the bolts or screws 6 are of the flat headed type. This type of bolt requires a counter-sink in the member in which it is used, and I therefore provide several depressions or sockets 7 for the reception of the heads of the bolts. These countersinks or depressions are preferably made by punching or pressing inwardly the side 2 of the member A in such manner that the depression conforms to the shape of the bolt heads which in this structure are tapered. The metal sheet which I find to be sufficiently strong for the purpose of a clamping member, is not thick enough to accommodate a sufficient number of threads to prevent stripping of the threads when the bolts are screwed up tight, and for this reason I provide circular openings in the side 3 and I turn or press the contiguous metal inwardly so as to form elongated sleeves or sockets 8, as clearly shown in Fig. 2. These sleeve portions 8 thus formed are considerably longer than the thickness of the sheet metal, hence they may be provided with a sufficient number of threads to receive the threaded end of the bolt 6 and allow the bolts to be screwed up tight without stripping the threads. It will be observed that with this construction I am enabled to dispose the bolts comparatively close to the trolley wire, and in this manner form a very effective clamp.

While I may use any type of device for suspending the hanger from the usual messenger wire, I prefer, on account of simplicity and convenience of manufacture, to use a piece of strap metal 10. By using strap metal I am enabled to attach the suspension member 10 to the member A in a very simple manner. Referring to the drawings, it will be seen that the lower end of the strap suspension member 10 projects downwardly through an elongated slot 11, which is punched in the curved portion 1 of the member A preferably before the metal sheet is formed up. The lower end of the strap metal extends between the side members 2 and 3 of member A, and is provided with a circular opening or hole 12, through which one of the bolts 6 passes. In the structure shown the center bolt 6 is used for this purpose.

The suspension member 10 may be attached or connected with the messenger wire in any suitable manner. In the structure shown the upper end of the strap 10 is doubled back on itself to form a hook or elongated slot 13, in which the messenger wire may work and the free end 14 of this strap is preferably turned laterally and then at right angles thereto to prevent the hanger from being displaced from the messenger wire. This forms in effect an elongated slot, which is closed by the right angle end 15 in one direction, but this end is sufficiently spaced from the strap 10 to enable it to be hooked over the messenger wire by first placing the hanger substantially parallel to the messenger wire, then entering the messenger wire into the slot 13, and then turning the hanger downwardly at substantially right angles to the messenger wire.

What I claim is:

1. In a catenary hanger, the combination of a one-piece member having substantially parallel sides and opposed lips for gripping the trolley wire, bolts passing through the sides of said member for drawing the lips into gripping engagement with the wire, and a suspension member extending through said member and between the sides thereof and attached thereto by one of said bolts.

2. A catenary hanger comprising a U-shaped piece of sheet metal having its opposed edges formed to engage a trolley wire, and an opening in the bend thereof, a suspension member extending through said opening and disposed between the sides of said U-shaped member, and a clamping bolt extending through said U-shaped member and suspension member.

3. A catenary hanger comprising a piece of sheet metal, doubled upon itself and having its opposed edges formed as wire engaging lips, and having an in-standing threaded sleeve in one of the sides of said piece of metal, a portion of the metal being formed inwardly to form a countersunk depression in the other side thereof opposite said threaded sleeve, and a clamping bolt having its head seated in said countersunk depression and screwed into said threaded opening.

4. In a catenary hanger, the combination of a clamping member formed from a single piece of metal, having opposed jaws formed to grip the trolley wire, and having an opening, a suspension member extending through said opening and positioned between the sides of said gripping member, and means for securing said gripping member to said suspension member and for clamping said jaws upon the trolley wire.

5. In a catenary hanger, the combination of a one-piece U-shaped clamping member substantially as thick as the diameter of

the wire to be clamped, and having substantially parallel side portions, and holding lips formed at the lower edges of said sides, an opening in said clamping member, 5 and a strap metal suspension member having its end projecting through said slot, and a clamping bolt for drawing the sides of said clamping member together to grip the wire therebetween, and for securing said 10 suspension member to said clamping member.

6. In a catenary hanger for trolley wires, the combination of a single piece of sheet metal doubled upon itself and having a slot 15 and having openings in the opposite sides of said piece, the opposed edges of said sides being formed as wire engaging lips, the metal contiguous to said openings being pressed inwardly and forming in one side 20 a bolt head seat and in the other side a socket, a suspension member disposed substantially at right angles to said piece of metal and projecting through said slot between the sides of said piece of metal, and 25 a clamping bolt passing through said suspension member into threaded engagement with said socket, and having its head seated in said seat.

7. In a catenary hanger for trolley wires, 30 the combination of a single slotted piece of sheet metal doubled upon itself and having the opposed edges of its side portions formed as wire engaging lips, and having openings in the opposite sides of said piece 35 of metal, the metal contiguous to said openings being pressed inwardly and forming

in one side a bolt head seat and in the other side a socket, a suspension member passing through said slot between the sides of said piece of metal, and a clamping bolt in said 40 openings, passing through said suspension, and having its ends substantially flush with said sides.

8. The combination of a single piece of sheet metal bent double to form a U-shaped 45 member of substantially the thickness of the trolley wire to be suspended and having its edges formed for engagement with the trolley wire, said U-shaped member having opposed holes in the sides thereof, the metal 50 contiguous to the hole in one side being thrust inwardly to form a countersink and in the other side to form a threaded sleeve, a strap metal supporting member passing through said slot and having its end positioned between said countersink and said sleeve to prevent substantial movement thereof and having a hole alined with said 55 opposed holes, and a clamping bolt passed through the hole in one side of said U-shaped member and through the hole in the suspension strap and threaded into said threaded sleeve.

In testimony whereof I have signed my name to this specification, in the presence 60 of two subscribing witnesses, on this 6th day of February A. D. 1912.

GLENN HENRY BOLUS.
